UNITED STATES PATENT OFFICE.

ARNOLD STUCKI, OF PITTSBURGH, PENNSYLVANIA.

ROLLER SIDE BEARING.

1,135,413.

Specification of Letters Patent. Patented Apr. 13, 1915.

Original application filed July 25, 1912, Serial No. 711,456. Divided and this application filed May 19, 1913. Serial No. 768,519.

To all whom it may concern:

Be it known that I, ARNOLD STUCKI, a resident of Pittsburgh, in the county of Allegheny and State of Pennsylvania, have invented a new and useful Improvement in Roller Side Bearings, of which the following is a specification.

This invention relates to side bearings for railway cars.

10 The object of the invention is to provide a side bearing which is practically frictionless under all service conditions, whether normal or abnormal, and which performs all other functions of side bearings, which is 15 efficient and durable in service, and which is simple in construction and therefore inexpensive both as to first cost and as to upkeep.

The invention comprises the construction 20 and arrangement of parts hereinafter described and claimed.

In the accompanying drawings, Figure 1 is a plan view of a side bearing embodying the invention; Fig. 2 is in part a side elevation and in part a vertical longitudinal section thereof; and Fig. 3 is in part an end view and in part a vertical cross section thereof.

The present application is a division of 30 my prior application for roller side bearing, filed July 25, 1912, Serial No. 711,456.

As illustrated in the drawings the bearing comprises a suitable frame or housing 1 arranged for attachment to the bolster 2, but 35 obviously said frame or housing may be integral with the bolster. As shown, said frame or housing is adapted for a straight bolster, but it can be readily adapted to a tapering bolster. The frame or housing is 40 provided with a bottom 3, side walls or barriers 4, end walls or barriers 5, and with suitable ears or lugs 6, perforated for the reception of rivets or bolts for securing said frame or housing to the bolster.

45 The bottom 3 provides a suitable bearing surface for the anti-friction member 8, which bearing surface may be either integral with the bottom, or, as shown, formed by a separate, hardened, steel plate 9 secured to the frame or housing by rivets 10 or the like. The anti-friction member 8 is 50 shown as a plain-faced cylindrical roller 8, which has a rolling movement upon the bearing surface, but makes only a partial rotation, and as it rolls first in one direction

and then in the other, it is in effect a rocker member. This rocker member may be made of other form than circular in cross section, and when in the form of a roller may be slightly conical or tapered instead of cylindrical, in which event the housing will be curved on an arc to correspond with the taper of the cone.

The bearing surface 9 on which the member 8 rocks or rolls is shown as level or horizontal from end to end so that the member 8 travels thereon without other than rolling friction, and without the necessity of lifting the car body as it rocks or rolls toward the ends of the housing or frame. 70 The bearing therefore permits a freer swiveling of the truck underneath the car body than in those types where the rolling or rocking member as it moves from the center of the bearing toward the ends is compelled to roll up an incline.

The side and end walls or barriers of the frame or housing are for the purpose of confining the rocking member and preventing it from escaping under normal operating 80 conditions, and are therefore of material height, extending fairly close to the top of the member 8, which projects slightly thereabove and has its upper surface exposed for directly supporting the upper bolster member 2^a. The end walls or barriers have their upper portions substantially vertical, as shown in Fig. 2, so that the roller 8 cannot roll up over the same, said end walls forming absolute stops to limit the travel of the 90 rocker member in both directions. The top edges of the side and end walls are broad and flat and form an efficient and satisfactory side bearing even if the roller is lost in a wreck or from other cause.

To prevent the housing from accumulating dirt, which would clog the movement of the rocking member, the walls are preferably of open or skeleton construction, the 100 end walls being provided with large openings 11 extending for the full width of the housing and for a considerable distance upwardly, while the side walls 4 are provided with large openings 12 at the central portions thereof. As a consequence the walls or barriers are practically supported upon posts or columns 13, leaving large openings at the level of the bearing surface, both at the ends and sides, through which snow, 105 ice, dust, dirt and other foreign material can 110

readily escape, so as to prevent retarding the movement of the rocking member. The side and end walls or barriers are strengthened and stiffened by horizontal ribs or flanges 14 and vertical ribs or flanges 15.

It is desirable to provide suitable means for returning the rocking member to central position in the frame or housing whenever the bolsters separate, in order that it 10 may be in proper position when the bolsters again come together and move relative to each other. On account of the level or horizontal position of the bearing surface 9, an ordinary roller would not automatically 15 return to central position upon separation of the bolsters. To provide for this the rocking member or roller is arranged to return to central position by a counterpoise acting by gravity. As shown, the roller 8 20 is provided with an opening or openings 16 on one side of its geometric axis, leaving the opposing side 17 solid so that its center of gravity is not at the geometric axis but somewhere within the solid and heavier 25 portion 17. Consequently, on a horizontal surface this roller will come to rest with its center of gravity as low as possible, or in the position shown in Fig. 2. The result is that it is self-centering by gravity whenever the bolsters separate. It is also desirable 30 to provide means to prevent the rocking member from shifting on the bearing surface so that it cannot become displaced under heavy end shocks or sudden longitudinal blows on the car. This result may be secured in several ways. As shown, the base 35 or bearing surface 9 is provided with projections or teeth 18 which engage notches or recesses 19 in the periphery of the solid portion 17 of the roller 8, said notches extending for a sufficient distance around the periphery of the roller to provide for the necessary travel. The teeth 18 and recesses 19 40 may extend the full length of the roller and from side to side of the bearing surface, but preferably are considerably shorter and ex- 45

tend only a short distance on either side of the median longitudinal plane of the bearing. It is preferred to have the teeth 18 on the bearing surface and the recesses 19 on the roller, for the reason that if the recesses were formed in the bearing surface they would form pockets to accumulate dirt.

In the bearing described the rocking member is free to rock or roll on a level or 55 horizontal bearing surface, without other than rolling friction and without either rising or falling as it moves. Consequently, it travels with the greatest facility with the swiveling of the truck, and by reducing friction assists in the free swiveling of the truck under the car body. The interengaging teeth and recesses on the bearing surface and the rocking member prevent the rocking member from slipping on the bearing surface, and 60 also prevent it from being shifted out of normal position by end shocks of the car. The counterpoise construction described provides very simple means for returning the rocking member to central position 70 whenever the bolsters separate.

What I claim is:—

A side bearing for railway cars, comprising a housing for the lower bolster having its bottom forming a bearing surface and 75 provided with side and end walls or barriers having flat upper surfaces and provided with openings at the level of the bottom bearing surface, and a cylindrical eccentrically loaded roller in said housing and 80 traveling on the bottom bearing surface thereof, said bottom bearing surface and the roller being provided with interengaging teeth, whereby when the upper bolster member rises the roller returns to central position in the housing.

In testimony whereof, I have hereunto set my hand.

ARNOLD STUCKI.
